PRESSURE CASTING APPARATUS

Raymond J. Schultz, Madison, Wis., assignor to
 Madison-Kipp Corporation, Madison, Wis., a
 corporation of Wisconsin

Application April 1, 1936, Serial No. 72,161

10 Claims. (Cl. 22—68)

The present invention relates to pressure casting apparatus and, particularly, to that type of apparatus wherein plunger means function to transfer metal in a moldable state from a container to a mold and compress it therein.

It is an important object of the invention to provide means whereby transference of the entire charge of metal from the container or well to the mold may be effected before the metal is placed under pressure, such, for instance, as would result from passage of the metal into the casting cavity or through the ingate. Thus, there is avoided the danger of metal under high pressure escaping from between the die and the well or container during the transferring operation. Furthermore, the absence of pressure on the metal with the arrangement referred to obviates the necessity of providing a tight fit between the metal well and the mold. This is particularly advantageous with bottom-gated, multi-part molds, as will appear later.

Another important feature of the invention is the provision of means, adapted for ready adjustment, whereby the desired transference of the metal charge to the mold before the metal is placed under pressure may be accomplished irrespective of the size of the casting cavity of the mold used.

A further object is the provision of means for readily adjusting the position of the metal receiving well so as to permit the use of different sized molds. Means are also included to insure proper alignment of the mold and the well during the metal transferring operation.

Simplicity and sturdiness of design, and efficiency of operation, whereby the machine is especially adapted for high pressure casting of high temperature metals, are further features of the invention. Other objects and advantages will appear hereinafter.

Reference is had to the accompanying drawings which illustrate a practical embodiment of the invention applied to a semi-automatic type of die casting machine.

Figure 1 is a front elevation of the die casting machine with certain parts in section to show the two-part die in closed position, ready to receive the charge of metal from the well.

Fig. 2 is a section on line 2—2 of Fig. 1, a number of the parts being shown in elevation.

Fig. 3 is an enlarged fragmentary section similar to a portion of Fig. 1, but showing the plunger raised and the metal charge moved into the die.

Fig. 4 is a perspective of one of the well adjusting members; and

Fig. 5 is a vertical section of the metal plunger and power piston coupling.

In the drawings, the die casting machine is shown as comprising a framework made up of a base 6 having legs 7 and supporting a hollow frame body 8. Body 8 is open at the bottom and base 6 at the top, as indicated at 9, to provide free space for the plunger operating mechanism described later. Machine screws 11 or the like secure base 6 and the frame body 8 together about their abutting edges.

Frame body 8 has an upright extension or hot plate 12 to which the fixed half 13 of the die is removably secured in any suitable manner. The movable half 14 of the die is detachably affixed to one end of a ram 16 mounted for reciprocation in an opening 17 extending through a second upright 18 on the opposite end of the machine. A pinion 19 is mounted in standard 18 and meshes with gear teeth 21 on ram 16, so that rotation of the pinion in one direction serves to open the die, and rotation in the opposite direction serves to close it. Hand wheel 22 forms the operating means for the pinion.

Toggle means are interposed between the opposite end of ram 16 and a portion 23 of the frame body 8 to lock the die in closed position, as shown in Fig. 1. The toggle means comprise 30 a link 24 pivotally connected at 25 to the ram and also pivotally connected at 26 to a second link 27. The latter is pivotally connected at 28 to the frame, this pivotal connection being adjustable by set screw means 29, so that the toggle 35 locking mechanism will function properly when used with dies of different thicknesses.

An upright link 30 is pivotally connected at 26 to the toggle means for operating the same. The lower end of this link pivotally connects at 31 with a lock lever 32 pivotally mounted at 33 on a leg 7 of the machine. With the parts in the position of Fig. 1, if the operator depresses the left end 34 of lever 32, link 30 will break the toggle formed by links 24 and 27 upwardly, so that hand wheel 22 may be turned to quickly open the die. To close the die and lock it, hand wheel 22 is rotated in the opposite direction, and, as the die part 14 approaches closed position, the operator steps on the opposite end 35 of lever 32. This causes link 30 to straighten out the toggle and thus tightly lock die part 14 against stationary die part 13.

The closed die, as most clearly shown in Fig. 3, has a casting cavity 36, a restricted ingate 55

passage 37 and a communicating, cylindrical pressure chamber 38 which opens at 39 on the bottom face of the die. Chamber 38 is located on the parting line of the die with a portion 5 of the chamber formed in each half of the die. This chamber is adapted to receive the charge of molten metal for the die through its open bottom end 39, the metal then being forced through ingate 37 and compressed under high 10 pressure in the die cavity 36 by the metal supplying, transferring and compressing means now to be described.

Frame body 8 has a horizontal portion 41 formed with a vertical, cylindrical portion 42 15 having a passage 43 extending therethrough. Snugly, but slidably, mounted in passage 43 is a cylindrical molten metal magazine or well 44 having a removable bushing or liner 46. The well is rabbeted at 47 and the liner flanged at 48 to 20 support the latter in place in the well, but permit its removal for renewal purposes. Liner 46 is arranged in exact alinement with cylindrical pressure chamber 38 in the closed die, and its interior diameter corresponds substantially to 25 that of the pressure chamber.

Well 44 has a flange 49 substantially encircling its upper end. Surrounding the well between flange 49 and the upper end of cylindrical portion 42 of the machine frame, is a series of 30 stacked, ring-like members 51. These members serve to support the upper end of the well in close proximity to the bottom face of the closed die, as shown in Figs. 1 and 3. One of the ring-like members 51 is shown in perspective in Fig. 4. 35 Some of these members preferably are made of different thicknesses for a purpose explained later.

In order to insure exact alinement between well liner 46 and pressure chamber 38, guide pins 40 52, 52 are mounted on the upper end of well 44 and project snugly in corresponding sockets 53, 53 in the bottom edge of stationary die part 13 (see Figs. 2 and 3).

A plunger 54 is mounted for reciprocation in 45 the lower open end of metal well 44 and controls the metal-receiving capacity thereof. When this plunger is in its lowermost position, as shown in Fig. 1, and the movable die part 14 is retracted, molten metal from any convenient source of supply 50 is ladled by the operator into the well above the plunger until well space 55 (Fig. 1) is substantially full. The die is then closed by manipulation of hand wheel 22, and certain power means, described later, set into operation to raise 55 plunger 54. The plunger transfers the charge of molten metal 56 from the well into pressure chamber 38 (as shown in Fig. 3), and then continues its upward movement in the pressure chamber, with which it has a rather close fit, to 60 force the metal through ingate 37 and into the die cavity 36. Plunger 54 is then operated to lower it into the well, the die is opened and the casting removed. The machine is now ready for the next casting operation.

65 The means for operating metal plunger 54 comprise a power piston 57 having a piston rod 57' connected to metal plunger 54, the piston 57 operating in a cylinder 58 supported by arms 59, 59 depending from the frame of the machine. These 70 arms are bolted or otherwise rigidly secured at 60, 60 to the frame body 8. Cylinder 58 is pivotally connected at 61, 61 to the lower ends of arms 59, 59 so as to permit vertical swinging movement of the cylinder for a purpose mentioned 75 later. Cylinder 58 has suitable ports 62, 63

adapted for the connection of hose or pipe, whereby compressed air or other motive fluid may be admitted to and exhausted from each end of the cylinder to positively move piston 57 in the desired direction. A suitable valve (not shown) is located at a convenient place on the machine for manipulation by the operator to cause movement of power piston 57 as desired.

A longitudinally adjustable connection is provided between metal plunger 54 and piston rod 10 57', so that the lowermost position of the plunger, i. e., the position of Fig. 1 with piston 57 against the lower end of cylinder 58, may be changed at will. Thus, there are present, for a purpose explained later, means for varying the volume of 15 the space 55 in the well above plunger 54 and, hence, the size of the charge of metal 56 which this space receives for transference to the die.

The adjustable connection referred to comprises a cylindrical coupling assembly, including a main 20 coupling member 64 and a complementary, semi-cylindrical coupling member 65. Machine screws 66, 66 serve to secure these coupling members together, but when the screws are removed, member 65 may be separated from member 64 on lines 25 67, 68, and 69. When assembled, the coupling presents a chamber 70, an upper opening 71 through which plunger 54 freely extends and an annular groove 72 in which is located an annular flange 73 on the plunger. The upper end of piston rod 57' is threaded and extends into a threaded opening 74 in a base portion 75 formed on coupling member 64. A lock nut 76 for the coupling is also provided.

It will thus be seen that the coupling assembly 35 may be rotated on piston rod 57' to raise or lower plunger 54 to any desired position in the metal well, whereupon the coupling is secured by the lock nut. Both the coupling and the lock nut have knurled surfaces in order to facilitate hand 40 manipulation thereof. Operating tool recesses 77 are also provided in lock nut 76. The diameter of coupling groove 72 is somewhat greater than that of plunger flange 73. This permits such lateral movement of the parts as may be necessary 45 to compensate for any misalignment between metal well 44 and pressure chamber 38, and the plunger operating mechanism described.

If, during the die charging operation, the charge of metal 56 were placed under pressure 50 before plunger 54 entered pressure chamber 38, which pressure for instance would be created by resistance of the metal to free passage through ingate 37 and into the die cavity, molten metal under high pressure would escape from between 55 the upper end of well 44 and the bottom of the closed die, unless a tight fit were provided between these parts. In order to eliminate this danger and obviate the necessity of a close fit between the top of the well and the multi-part 60 die, particularly part 14 thereof which must be adapted for free opening and closing movement, provision is made for transferring the entire charge of metal 56 from the well to the closed die before the metal is placed under pressure. 65

This is accomplished by properly proportioning the volumetric capacities of pressure chamber 38 and well space 55 (Fig. 1) with reference to the size of the particular casting being made, i. e., the volume of metal necessary to fill die cavity 70 36 and extend sufficiently far down into pressure chamber 38 to permit plunger 54 to act thereon and force the metal into all parts of the cavity. This volume determines the size of the metal charge 56 which is to be placed in metal well 44. 75

The volume of molten metal necessary for the particular casting being known, and plunger 54 being in its lowermost or charge-receiving position of Fig. 1 with the die open, the adjustable coupling between plunger 54 and piston rod 57 is rotated to move plunger 54 up or down in well 44 until well volume 55 above the plunger is equal to the volume of metal required to make the casting. Molten metal is then ladled into the well 10 until it is substantially full, and the die is closed. The power means described are then set into operation to cause plunger 54 to rise and move the metal charge 56 into pressure chamber 38. This transference of the metal charge into chamber 38 is effected before the metal is placed under pressure by making the pressure chamber of a capacity sufficient to receive the entire charge of metal for the casting being produced, and by so shaping pressure chamber 38 as to permit free movement 20 of the charge of metal therethrough until plunger 54 enters the pressure chamber, as shown in Fig. 3. Thus, by the time the metal charge 56 is placed under pressure, which does not occur until the metal seeks to pass through the restricted ingate passage 37 and into the restricted parts of the die cavity, plunger 54 has passed beyond and sealed the joint between the die parts and the top of well 44 so as to preclude all possibility of metal under pressure escaping at this point.

30 In order to realize the advantages of the present improvements when a die for producing a smaller or a larger casting is substituted, it is necessary to maintain the above described relationship between the capacity and shape of pressure chamber 38 in the die and the capacity of well space 55, and the volume of metal necessary to make the casting. In other words, the capacity of well space 55 must be changed so that, when full, it will contain a metal charge of proper 40 volume to meet the requirements of the casting being made. Likewise, the volumetric capacity of the pressure chamber 38 in different dies will be controlled by the size of the casting.

Ring-like members 51, as stated, serve to hold well 44 in close proximity to the bottom of the die. When the die is open and die part 13 removed, well 44 with its liner 46 may be lifted out from above for renewal, repair or other purposes. With well 44 removed, certain of the ring-like 50 members 51 may be interchanged for other similar members of different thicknesses, or certain of them may be added or removed, in order to vary the height at which these members support well 44 when the latter is in place. Thus, provision is made to accommodate the height of the well to different sized dies, the bottom surfaces of which are disposed at different levels when mounted in the machine.

Should it be desired to remove plunger 54 for 60 renewal or other purposes, screws 66, 68 are first removed and then coupling part 65. Piston rod 57 and cylinder 58 may then be swung towards the right on pivots 61, 61 (Fig. 1) to disconnect coupling member 64 from plunger 54, 65 whereupon the plunger is pulled through the bottom of well 44; or, when coupling member 65 is removed and there is no die in the machine, well 44 and its liner may be removed and plunger 54 tilted in opening 43 to disengage it from coupling 70 member 64 and permit its withdrawal from the machine.

Although the present improved pressure casting apparatus has been specifically described with reference to its use with molten metal, it is 75 apparent that it is equally as well adapted for

the efficient production of high quality castings from metal in any other suitable moldable condition, such, for instance, as the plastic or so-called pasty state.

While a practical embodiment of the invention now in use has been illustrated and described herein, it is obvious to those skilled in the art that various changes in the construction may be made within the scope of the invention, except as the same may be limited by the appended claims. 10

What is claimed is:

1. The combination in pressure casting apparatus of a support; a mold on said support, said mold having a casting cavity and a pressure chamber communicating therewith and opening 15 onto the exterior of the mold; a substantially upright, tubular metal well mounted on the support with its upper end alined with said pressure chamber, said well having a flange at its upper end and being vertically adjustable to locate it 20 in close proximity to the bottom of the mold; a plurality of ring-like members, at least some of which are of different thicknesses, mounted on the well between said flange and the frame of the machine to maintain the well in position; and a plunger mounted in the lower end of the well for reciprocatory movement in the well and the pressure chamber to transfer metal from the well into said chamber and thence into the mold cavity. 30

2. The combination in pressure casting apparatus of a support; a mold mounted on said support, said mold having a cavity and an opening on the exterior of the mold communicating with said cavity; a metal well adjustably mounted on said support and having an opening alined with said opening in the mold; a plurality of different sized removable elements interposed between the support and a portion of the well to maintain the well in close proximity to the mold; and 40 plunger means for transferring metal from the well to the mold. 35

3. In a die casting machine, the combination of a frame; a bottom-gated, separable die comprising a fixed die half and a die half adapted for horizontal movement to open and close the die, the closed die having a casting cavity and a vertically disposed, vertically split, cylindrical pressure chamber, half of which is formed in each die half, communicating with the die cavity 45 and opening onto the bottom of the die; a stationary, vertically disposed, tubular well mounted on the frame beneath the die with its upper open end in alinement with the pressure chamber in the closed die, but slightly spaced from 50 the bottom of the die to permit free operation of the movable die half; and a plunger in the lower portion of the well adapted for movement through the well and into the pressure chamber 55 to transfer metal from the well into said chamber and thence into the die cavity, said pressure chamber permitting free passage of the metal whereby leakage of metal between the closed die and the well is prevented. 60

4. The combination in pressure casting apparatus of a bottom-gated, separable die comprising a plurality of die parts adapted for substantially horizontal, relative movement between die open and die closed positions, the closed die having a casting cavity and a split pressure chamber 70 formed by the die parts, said pressure chamber communicating with the die cavity and opening onto the bottom of the die; a tubular, upright well positioned beneath the closed die with its upper open end in alinement with the pressure 75

chamber in the die but slightly spaced from the bottom of the die to permit freely said relative movement of the die parts; and a plunger in the well adapted for movement therethrough and into the pressure chamber to transfer metal from the well into said chamber and thence into the die cavity, said pressure chamber permitting free passage of the metal whereby leakage of metal between the closed die and the well is prevented.

5. The combination of claim 4, wherein said well is adapted, when the plunger is lowered, to receive a metal charge of sufficient volume to fill the die cavity and extend into the pressure chamber, further characterized in that the pressure chamber in the closed die has a volume sufficient 10 to receive said entire metal charge and is shaped to permit free movement of the entire charge therethrough until the plunger enters the pressure chamber, whereby to prevent escape of metal under pressure from between the well and the closed die when the plunger forces the metal from the pressure chamber into the die cavity.

6. The combination in pressure casting apparatus of a bottom-gated, separable die comprising a plurality of die parts adapted for substantially horizontal, relative movement between die open and die closed positions, the closed die having a casting cavity and a split pressure chamber formed by the die parts, said pressure chamber communicating with the die cavity and opening onto the bottom of the die; a tubular, upright well positioned beneath the closed die with its upper open end in alignment with the pressure chamber in the die but slightly spaced from the bottom of the die to permit freely said relative movement of the die parts; a plunger in the well adapted for movement therethrough and into the pressure chamber to transfer metal from the well into said chamber and thence into the die cavity; and means for limiting retraction of the plunger, the well being adapted, when the plunger is at its limit of retraction, to be filled with a charge of metal, which charge is of sufficient volume to fill the die cavity and extend into the pressure chamber, and the pressure chamber having a volume greater than that of said entire metal charge and being so shaped as to permit free movement of the entire charge therethrough until the plunger enters the pressure chamber, whereby to prevent escape of metal under pressure from between the well and the closed die when the plunger forces the metal from the pressure chamber into the die cavity.

7. The combination in pressure casting apparatus of a bottom-gated, separable die comprising a plurality of die parts adapted for substantially horizontal relative movement between die open and die closed positions, the closed die having a casting cavity and a split pressure chamber formed by the die parts, said pressure chamber communicating with the die cavity and opening onto the bottom of the die; a stationary, upright, tubular well located beneath the closed die with its upper open end in alignment with the pressure chamber in the die, said upper end of the well being flat and slightly spaced from the bottom of the die to permit freely said relative movement of the die parts; and a plunger in the well adapted for movement therethrough and into the pressure chamber to transfer metal from the well into said chamber and thence into the die cavity, said pressure chamber permitting free passage of the metal, whereby leakage of metal between the closed die and the well is prevented.

8. The combination in pressure casting appa-

ratus of a split gate, separable die comprising a plurality of die parts adapted for relative horizontal movement towards and from each other during closing and opening of the die, the closed die having a casting cavity and a vertically, 5 axially split pressure chamber formed by the die parts, said pressure chamber communicating with the die cavity and opening onto the bottom of the die; a vertical, tubular metal well positioned below said closed die and having its upper open 10 end in alignment with the pressure chamber in the die; and a plunger in the lower part of the well adapted for movement therethrough and into the pressure chamber to transfer metal from the well into said chamber and thence into the die 15 cavity, said well being adapted, when the plunger is retracted, to receive a metal charge of sufficient volume to fill said die cavity and extend into the pressure chamber, and said pressure chamber having a volume sufficient to receive said entire 20 metal charge and being so shaped as to permit free movement of the entire charge therethrough until the plunger enters the pressure chamber, whereby to prevent escape of metal under pressure from between the well and the closed die 25 when the plunger forces the metal from the pressure chamber into the die cavity.

9. The combination in pressure casting apparatus of a bottom-gated, separable die comprising a plurality of die parts adapted for substantially horizontal, relative movement between die open and die closed positions, the closed die having a casting cavity and a split pressure chamber formed by the die parts, said pressure chamber communicating with the die cavity and opening 30 onto the bottom of the die; a tubular, upright well positioned beneath the closed die with its upper open end in alignment with the pressure chamber in the die but slightly spaced from the bottom of a die part adapted for movement with 35 reference to said well in opening and closing the die, whereby to permit freely said relative movement of the die parts; and a plunger in the well adapted for movement therethrough and into the pressure chamber to transfer metal from the well 40 into said chamber and thence into the die cavity, said pressure chamber permitting free passage of the metal whereby leakage of metal between the closed die and the well is prevented.

10. The combination in pressure casting apparatus of a bottom-gated, separable die comprising a plurality of die parts adapted for substantially horizontal, relative movement between die open and die closed positions, the closed die having a casting cavity and a split pressure chamber 55 formed by the die parts, said pressure chamber communicating with the die cavity and opening onto the bottom of the die; a tubular, upright well positioned beneath the closed die with its upper open end in alignment with the pressure chamber in the die but slightly spaced from the bottom of the die to permit freely said relative movement of the die parts; a plunger in the well adapted for movement therethrough and into the pressure chamber to transfer metal from the well 60 into said chamber and thence into the die cavity; means for limiting retraction of the plunger, the well being adapted, when the plunger is retracted, to receive a metal charge of sufficient volume to fill the die cavity and extend 65 into the pressure chamber, and the pressure chamber in the closed die having a volume sufficient to receive said entire metal charge and being so shaped as to permit free movement of the entire charge therethrough until the plunger 70

75

enters the pressure chamber, whereby to prevent escape of metal under pressure from between the well and the closed die when the plunger forces the metal from the pressure chamber into the die cavity; and means for adjusting said plunger limiting means, so as to vary the limit

of retraction of the plunger and consequently the depth and capacity of the upright metal-receiving well, whereby to accommodate dies adapted to produce different sized castings.

RAYMOND J. SCHULTZ.
